UNITED STATES PATENT OFFICE.

CHARLES L. DAHLBERG, OF DES MOINES, ASSIGNOR OF ONE-HALF TO
ROBERT N. DAHLBERG, OF KEOSAUQUA, IOWA.

CAR-COUPING.

SPECIFICATION forming part of Letters Patent No. 251,839, dated January 3, 1882.
Application filed November 12, 1881. (No model.)

To all whom it may concern:

Be it known that I, CHARLES L. DAHLBERG, of Des Moines, in the county of Polk and State of Iowa, have invented an Automatic Car-Coupling, of which the following is a specification.

The object of my invention is to avoid the dangers and accidents incident to coupling rail-way-cars by means of common links and pins.

It consists, first, in forming a link that is adapted to be hinged to a draw-head in such a manner that cars having one of my links at each end will be automatically coupled together by hooks that project laterally from the links and readily uncoupled through the medium of levers that extend from the links in opposite directions from the hooks; second, in combining my link with a draw-head, a bolt, and a spring in such a manner that the spring in its normal condition will hold the link in line with the longitudinal center of the draw-head; third, in combining a lever with my link by means of a flexible rope or chain to facilitate the uncoupling of cars, all as hereinafter fully set forth.

Figure 1 of my accompanying drawings is a perspective view of my improved link. Fig. 2 is a side view of a draw-head having one of my links attached. Fig. 3 is a top view of two cars connected by means of my coupling and provided with my device for uncoupling without going between the cars. Jointly considered, these views clearly illustrate the construction, application, and operation of my complete invention.

a a are the parallel bars of my link. Each bar has a perforation, *b*, at its rear end. They are connected at their front ends by means of an inclined plane, *c*, that projects laterally and forward.

d is a hook, that projects laterally and inclines rearward from the front and connected ends of the bars *a*, and, in combination with the plane *c*, forms a cross-head. All the parts are preferably made of malleable iron and cast integral with each other. They may vary in size and configuration as desired.

f represents the cavity in a draw-head of common form opened at its sides by cutting away the side walls.

g is a pin or screw-bolt passed downward through perforations that extend vertically through the top and bottom portions, *h*, of the bifurcated front end of the draw-head, and also through the perforations *b* in the rear ends of the link-bars *a*, as required, to hinge the link in the cavity of the draw-head in such a manner as to retain it on its edge and allow it to swing laterally.

k represents a coil-spring surrounding the bolt *g*. Its upper end is fixed to or engages the draw-head and its lower end is fixed to or rests against the link in such a manner that in its normal condition the spring will retain the link in direct line with the draw-head, as required, to engage and interlock with a corresponding link carried by a corresponding draw-head on another car.

m m are levers extending downward from rock-shafts *n*, that are mounted in suitable bearings attached to the front portions of the cars.

r r represent hand-levers that extend at right angles from the outer ends of the shafts *n* in such a manner that the shaft can be readily rocked thereby, as required, to operate the levers *m*, that are flexibly connected by means of cords or chains *s* with the ends of the inclined planes and levers *c*, that project laterally and forward from the hinged links.

In lieu of the compound levers combined with the rock-shafts, hand wheels and levers of various forms may be used for imparting motion to the hinged links and swinging them laterally, as required in the act of uncoupling.

In the practical operation of my invention thus constructed and applied the lateral and forward projections or cross-heads, *c d*, at the front ends of the hinged links will always be, when the links are in line with the cars, in parallel position relative to each other at both ends of a car, or two or more cars on the same track, so that whenever the cross-heads or inclined projections of two links come together as two cars meet the links will be pressed laterally and turned out of the way of the colliding ends of the draw-heads, and the instant the cars and draw-heads are separated by a rebound the hinged links, actuated by the springs *k*, will swing back into line and inter-

lock, as shown in Fig. 3, by means of the hooks *d*, that extend in opposite directions and pass through between the bars *a* to reciprocally overlap the planes *c*, that close the front ends of the links. The inclined planes thus serve to direct the abutting ends of two links whenever brought into contact by the movements of one car relative to another car on the same track.

To uncouple cars connected by means of my automatic coupling mechanism, I simply seize one of the hand-levers *r* outside of one of the cars and turn it toward the end of the car, as required, to rock the shaft *n* and actuate the lever *m* to draw upon the cord or chain *s*, and thereby pull upon the inclined plane *c*, that will serve as a lever in swinging the hinged link to disengage it from its counterpart hinged to the adjoining car.

To couple a car provided with my improved coupling to another car by means of a common open link and detachable pins, I simply form a second vertical perforation, *i*, in the draw-head, as shown in Figs. 2 and 3, and swing the hinged link laterally and fasten it out of the way, so as to allow the common link to be inserted in the cavity of the draw-head and secured by means of a pin passed downward through the perforations *i*, and also through the link.

I am aware that draw-heads having laterally projecting hooks have been hinged to cars to automatically couple cars; but my manner of forming a link and combining and operating

it with a draw-head and car is novel and greatly advantageous.

I claim as my invention—

1. The improved link for coupling cars, composed of the parallel and perforated bars *a b* and the cross-head or inclined-plane lever and hook *c d*, substantially as shown and described, for the purposes specified.

2. The link *a b c d*, in combination with a draw-head and a spring, substantially as shown and described, to operate in the manner set forth, for the purposes specified.

3. The link *a b c d*, hinged to a draw-head, the compound lever *m n r*, and the rope or chain *s*, substantially as shown and described, to operate in the manner set forth, for the purpose of uncoupling cars.

4. An improved car-coupling, composed of a link having an inclined cross-head adapted to perform the functions of a directing-plane and a coupling-hook at its front end and perforations at its rear end, a draw-bar having a cavity, *f*, at its front end, a pin or screw-bolt, *g*, a spring, and an operating-lever connected with the cross-head of the link by means of a flexible rope or chain, substantially as shown and described, to operate in the manner set forth, for the purposes specified.
